FIRE PLACE HEATING SYSTEM

Charles E. Goulding, Sr., Tampa, Fla.

Application June 4, 1953, Serial No. 359,455

1 Claim. (Cl. 126—123)

This invention pertains to heat transfer devices, and more particularly, to heating means adapted to be utilized in conjunction with fireplaces of conventional design and construction.

One of the primary objects of this invention is to provide a heating system which may be assembled as a unit for immediate installation within a fireplace, or which may be shipped in knock-down form for assembly in situ.

Another object of this invention is to provide a heating system of the type described which includes a prime heater, a heat accumulator or economizer, and a flue adapter, connected together to provide a sinuous path for the heat combustion products whereby the optimum amount of heat transfer is achieved between the system and the ambient atmosphere.

Other and further objects and advantages of this invention will become apparent from a consideration of the following specification when read in the light of the annexed drawing, in which:

Fig. 1 is a front elevation of a conventional fireplace and of a heating system constructed in accordance with this invention;

Fig. 2 is a top plan view, taken on the line 2—2 of Fig. 1 looking in the direction of the arrows, and illustrating the disposition and arrangement of component elements of the heating system to which this invention relates; and

Fig. 3 is a cross sectional view taken on the line 3—3 of Fig. 2 and looking in the direction of the arrows.

Referring now more specifically to the drawing, reference numeral 1 indicates, in general, a conventional fireplace formed of brick, stone or other desirable materials. In the embodiment herein disclosed, the fireplace 1 includes a pair of oppositely disposed, longitudinally spaced and parallel side walls 2, 3, which connect at their inner edges with a pair of inwardly converging baffle walls 4 and 5, respectively. The adjacent inner edges of the baffles 4, 5, are, in turn, connected with the opposite ends of the back wall 6 positioned substantially parallel to the open face of the fireplace 1. As is clearly seen in Figs. 2 and 3, the base 7 of the fireplace 1 is provided with an exterior apron 8 longitudinally co-extensive therewith. In accordance with conventional practice, the fireplace 1 is provided with the customary chimney 9 including the well 10.

The heating system forming the subject-matter of this invention may be basically described as comprising three main substantially hollow, spaced and parallel heat transfer compartments consisting of a primary oil burning heater 11, a heat accumulator or economizer 12, and a flue adapter 13, all constructed of metal or other materials having a high degree of heat of conduction and having substantially rectangular transverse and longitudinal cross sectional configurations.

The primary heater 11 is provided with a bottom wall to which is rigidly secured the lower end of a centrally positioned oil burner support 15. The upper end of the support 15 terminates in an inwardly extending integrally

2

formed annular flange 16. The annular flange 16 snugly receives therethrough the cylindrical casing 17 of an oil burner generally designated by the reference numeral 18, preferably constructed in accordance with the teachings of my patent, No. 2,154,567, which issued on April 18, 1939. The upper end of the casing 17 is formed with a radial flange or shoulder 19 which is superposed on the annular flange 16 and may be fixedly or removably secured therein. The lower end of the oil burner 18 is provided with a fuel supply conduit 20 which projects laterally from one side wall 21 of the heater 11 and is connected with a fuel source to be described. The upper end 22 of the heater 11 is centrally apertured at 23 to afford ignition access to the oil burner 18, the aperture being normally closed by the cap 24.

The back wall 25 of the primary heater 11 is provided with a pair of horizontally spaced and aligned apertures 26, 27, which receive therethrough one end of the conduits 28, 29, respectively. The other ends of the conduits 28, 29 are connected to the interior of the heat accumulator or economizer 12 through suitable apertures (not shown) formed in and adjacent to the upper end of its front wall 30. As is clearly shown in Figs. 2 and 3, the back wall 31 of the heat accumulator 12 and the front wall 32 of the flue adapter 13 are provided with spaced aligned apertures adjacent to their lower ends and are adapted to receive therein opposite ends of a connecting pipe 33 having a larger diameter than either of the conduits 28 or 29.

The upper end of the flue adapter 13 is formed with a reduced neck portion 34 which connects with an elbow pipe section 35 projecting upwardly through a transverse fireplace throat sheet 36 for coupling with a plurality of flue pipes 37, 38 disposed within the chimney well 10.

As seen in Fig. 2, the fuel supply conduit 20 is connected directly with a conventional fuel control unit 39 having a manually operable control valve means 40. The control unit 39 connects, in turn, through conduit 41 with an oil fuel reservoir 42 rigidly supported by brackets 43 which are fixedly secured to and project laterally from the side wall 21 of the primary heater 11. Preferably, this assembly is positioned to the right of the system as viewed in Fig. 1.

The heating system units and their component parts are of such dimensions as to permit the heat accumulator 12, the flue adapter 13 and a substantial portion of the primary heater 11 to be substantially surrounded by the side and rear walls of the fireplace 1. The entire system is supported above the fireplace base 7 and apron 8 by adjustable legs 44.

A guard screen 45 extends across the open face of the fireplace 1 and is provided with a grill 46 at the left hand side thereof as viewed in Fig. 1. Directly behind the grill 46 an electric fan 47 is secured on suitable mounting means to base 8, whereby air from the ambient atmosphere may be drawn into the fireplace 1 and circulated between the units 11, 12 and 13, and the air having become heated through contact therewith is reflected outwardly from the side walls 2, 3, baffles 4, 5, and rear wall 6.

The maximum of heat exchange is achieved by forcing the products of combustion through a sinuous path through the units 11, 12 and 13 whereby the heated gaseous and solid particles of combustion are scrubbed against the walls thereof.

From the foregoing description it is seen that by rigidly connecting the heat exchange elements of this system together, together with their component parts, the system may be preassembled and installed as an integral unit, or if desired, it may be packaged in knock-down form and assembled in situ. In either form, the system is non-complex in construction and assembly, requires little

maintenance, and is relatively inexpensive to manufacture.

Having described this invention in detail, it will be understood that the embodiment thereof herein disclosed and illustrated is offered by way of example, and that the invention is to be limited only by the scope of the following claim.

I claim:

In combination with a fireplace including a pair of opposed side walls, baffles arranged angularly with respect to said side walls, a vertically disposed back wall extending between said pair of baffles, said fireplace further including a horizontally disposed base and a horizontally disposed apron, a heating system including first, second and third spaced, parallel heat transfer compartments defining a primary oil burning heater, a heat accumulator, and a flue adapter respectively, all of said compartments being rectangular in cross section, said primary heater including a horizontally disposed bottom wall, an oil burner support positioned centrally on said bottom wall and the upper end of said support terminating in an inwardly extending integral annular flange, an oil burner having a cylindrical casing snugly seated in said flange, the upper end of said casing being provided with an annular shoulder arranged above said flange, a fuel supply conduit connected to the lower end of said oil burner and extending laterally from one side of the primary oil burning heater, there being a plurality of spaced apart apertures in the

back wall of said primary heater, conduits extending through said apertures and connected to the interior of said heat accumulator, a pipe extending from the back wall of the heat accumulator to the front wall of the flue adapter, the upper end of the flue adapter being provided with a reduced neck portion, an elbow pipe section connected to said neck portion, flue pipes connected to said elbow pipe section, the heating system being positioned in the fireplace so that the heat accumulator, flue adaptor and a substantial portion of the primary heater are surrounded by the side and rear walls of the fireplace, a guard screen extending across the open face of the fireplace and provided with a grill, and an electric fan positioned directly behind said grill.
